ABSTRACT

Apparatus is provided for printing available coded data having type wheels individually arrestable in a printing position and resiliently connected to a drive shaft through springs. Idler means are provided for each type wheel and each idler means if firmly coupled with its respective type wheel and resiliently driven by a shaft. Means including at least two locking wheels are positioned independently of each idler means and of each other, with the means including the locking wheels being resiliently driven by the shaft. In addition, means are provided for arresting each locking wheel, with each said locking wheel being provided with stop means for avoiding advancement of the idler means as compared to each of the locking wheels, with the arresting means controlled by the data to be printed consecutively, being engaged alternately, one each for one printing operation.

**SELECTIVE PRINTER INCLUDING SETTABLE,
RESILIENTLY DRIVEN TYPE WHEELS**

This invention relates generally to print-out apparatus, and more particularly to a device for printing out available coded data with type wheels being individually arrestable in printing position and connected resiliently through spring means with a drive member.

In the field of data processing and transmission of intelligence as well as of measuring and controlling technique, there are often used printing units to visualize, for instance, electronically calculated or transmitted data. Due to the high operation speed of electronic structural elements, the connected printing units must be capable of operating very quickly to permit a good utilization of the existing equipment.

As for test data printers, it is additionally necessary to record the operational behavior of a machine or plant by means of numerical data and to keep such data accessible at any time. The real use of such data, however, is only made in a few cases so that a high expenditure for the printing unit is thus unjustified.

There are already known printing units controlled by punched card readers, and which, corresponding to the position of holes in a punched card, are printing individual information on a data carrier.

For this purpose, a stepping wheel driving the type wheel is resiliently coupled with a drive wheel. Sensing a hole in the punched card, the stepping wheel is stopped by the engagement of a pawl, while the drive shaft goes on turning with undiminished speed. The type wheel being coupled with the stepping wheel, the printing type selected at the moment of engagement of the pawl in the stepping mechanism stays for a time in the printing position, thus permitting printing. Thereafter, the stepping wheel is released.

This will be accelerated to such an extent by the spring connected with the drive shaft that it returns to the original position of angle of rotation relative to the drive shaft and it is prepared for the selection of another printing type.

Such printing units allow a relatively slow printing sequence, the selection of the next printing character, and the preparation of the next printing operation being only possible when the stepping wheel is again in the defined position of angle of rotation relative to the drive shaft. Upon an earlier income of the arresting impulse, a wrong type is released for printing.

There are also known printing units comprising type wheels connected through torsion springs with one of common drive shaft. Only part of the circumference of the type wheels is fitted with printing types, the other part being provided with pawls. During a printing cycle, the drive shaft changes its sense of rotation. Thus this permits the corresponding pawls to engage the teeth of the type wheel. During the subsequent return movement, release of the type wheels for the preparation of a new printing cycle is accomplished.

Also, in this case, the printing sequence is slowed due to the fact that, upon termination of the printing, the springs must be relaxed each time before new printing information can be evaluated. It is necessary to brake and accelerate the entire system during each printing cycle. Therefore, a further slowing of the printing sequence is caused by this required alternate rotation of the shaft.

It is the object of this invention, therefore, to provide a unit for printing out available coded data with type wheels being individually arrestable in a printing position and resiliently connected through spring means with a drive member, with the preparation of the next printing operation being already possible when the spring, tensioned during the printing operation, has not yet reached its idle position.

Still another object of this invention is to provide for each type wheel an intermediate idler wheel resiliently by a shaft and firmly connected with the type wheel, with the intermediate wheel being provided with at least two locking wheels being resiliently driven by the shaft and each being arrestable by an associated one pawl, the advance of the idler wheel as compared to each locking wheel being avoided by stops, and

the pawls—controlled by the data to be printed consecutively—engaging alternately, each locking wheel for one printing operation.

And another object of this invention is to provide a device in which the printing of information is immediately followed by the setting for the next information without necessitating the return to the prior position. During the operation, the shaft is rotated at a constant speed. A rotation of 180° corresponds to one revolution of the type wheel such that, in the case of the two locking wheels, each semi-revolution of the shaft allows one character to be printed. In the idle position, the locking wheels as well as the idler are driven by the shaft in like manner. If, however, information to be printed is conveyed to an electronic register, one of the pawls engages the corresponding locking wheel providing the information in the register coincides with the type of the type wheel in the printing position. Due to the stopping of the locking wheel, it is avoided through the stop that the idler goes on turning, while the type wheel consequently remains in the desired position.

The second locking wheel, however, goes on rotating synchronously with the shaft. Upon termination of the printing, the locked locking wheel is released and, like the idler, is accelerated by the tensioned torsional spring until the position of the angle corresponding to the position of shaft is reached again. But the printing operation of the next character could be already prepared before by the other pawl engaging in the corresponding locking wheel. By stopping this locking wheel, the idler need not follow the new angle position of the shaft after the printing of the first character. It is stopped again before the relaxation of the spring, in order to print the next character. By contrast, the locking wheels are always returned to their initial position with respect to the shaft.

Another object of this invention is to provide a device in which there is an independent, rotary, coaxial arrangement of idler and locking wheels, with each wheel being driven by an appertaining further wheel fitted resiliently on a drive shaft. The coaxial provision of wheels required for the impression is realized by intermeshing of corresponding projections and recesses of the wheels.

Still even another object of this invention is to provide a device having a drive shaft with stops in order to avoid the advance of the other wheels. This is achieved by a steady pre-tension of the torsional springs, even when the whole printing unit is in the idle position. The advantage of such a provision is that sufficient spring power is obtained upon relaxation of the spring even shortly before reaching the stop. A quick and safe operation is thus obtainable.

A favorable structure is realized with the arrangement of the locking wheels on opposite sides of the idler, the latter exhibiting two projections in reverse order by 180° each of which engaging in a semi-circular slot provided in the appertaining locking wheel, the slots in the locking wheels being displaced relatively to each other by 180° in idle position. Then the idler is alternately stopped by the bilaterally arranged locking wheels, and the appertaining torsion spring is always tensioned again.

Still a further object of this invention is to provide a printing unit whose parts serve to select and prepare the printing types. They act alternately in time on the idler, and, consequently, on the type wheel connected to it. This will permit a very quick operation, with the parts thereof being subjected to strong accelerations and slow down response and working slowly and alternately.

Other objects and attendant advantages of this invention will become more readily apparent and understood from the following detailed specification and single sheet of accompanying drawings which illustrates a typical embodiment of a printing unit, with only the drive for one sole printing site incorporating features of the invention.

It is to be noted that several similar devices may be used within the range of a line printer, but it is also possible to provide other printing machines in this manner.

Referring now to the drawing, there is shown a printing unit having a drive shaft 1 which is fitted with a single-revolution clutch (not illustrated) which facilitates the initiation of each individual printing operation. By operating the clutch, the drive shaft 1 is turned counterclockwise by 180°. A bushing 2 is fixedly connected to the drive shaft 1, and it is provided with a slot 3 in which is fastened the core of a helical spring 4.

The outer end of the spring 4 rests against the edge 5 of segment 6 of a wheel 7. The wheel 7 as well as wheels 10, 11, being also supported by corresponding bushings 35, 36, is pivotable with respect to shaft 1, and it is normally actuated through helical spring 4.

This helical spring 4 is normally biased to urge an edge 8 of a segment 6 against a cam 9 of the bushing 2. The same resilient synchronized arrangement is provided for wheels 10 and 11.

Locking wheels 12, 14 and an idler 13 arranged between them are pivotally mounted on an axle 27. The wheels 7, 10 and 11, are circumferentially formed with radially spaced teeth in the periphery thereof with all wheels having the same number of teeth in the present case. During an operation when no information is selected, viz. no printing operation, wheels 7, 10, and 11 are turned counterclockwise by 180° and wheels 12, 13, and 14 also turn clockwise by 180°.

Idler 13 is provided with two lateral projections or pins 15, 16, which are displaced relatively to each other by 180°. Pins 15, 16 engage in corresponding slots 17, 18 formed in the locking wheels 12, 14. In normal position, projection 15 rests against the upper edge 19 of wheel 12, and projection 16 rests against the lower edge 20 of slot 18. Semi-circular slots 17, 18 are normally not aligned with each other as view in the drawing.

In the event two successive pieces of information are to be printed, the selection of the first piece of information is made at the locking wheel 12, and of the second one at wheel 14. At the beginning of the first cycle, wheels 7, 10, and 11 are driven counterclockwise through the helical spring 4 by the revolution of drive shaft 1; they drive wheels 12, 13 and 14 with which they are constantly intermeshing so that these wheels are commonly turned clockwise. Idler 13 is constantly intermeshing with a transfer wheel 21 which, in turn, drives a wheel 22 of type roller 23. As soon as idler 13 starts to turn clockwise, type roller 23 is also moved clockwise.

There is provided at drive shaft 1 a coding plate (not illustrated) is delivering pulses to an electronic plotting panel, the pulses corresponding to the position of drive shaft concerned. These pulses are constantly compared with the information to be printed and stored in a register, and in case of conformity, one of the magnet systems 24, 28 gets a current impulse, attracting the appertaining armatures 25, 29 and causing the pawls 26, 30 to be inserted into a space between two adjacent teeth of wheels 12, 14.

Upon blocking of wheel 12, for instance, in such a way that the projection 15 of idler 13 is moved into engagement with the edge 19 of slot 17, whereby further rotation of wheel 13, and also of type roller 23 is thereby precluded. The selected character on type roller 23 is stopped, and remains in a printing position up to the moment of printing on paper or on another document.

While wheels 7, 12 and 13 are blocked this way, drive shaft 7 continues to turn, while helical springs 4 of wheels 7 and 10 are tensioned. Locking wheel 14 which did not yet participate in the selection of types, continues rotating due to the drive of helical spring 4 in wheel 11 whereby its speed remains constant.

Edge 20 of slot 18 moves over and relative to the projection 16 of the blocked idler 13. The printing operation properly speaking is carried out just before the termination of the 180° rotation of shaft 1 whereby the selected information is printed, and, immediately thereafter, pawl 26 is removed from the path of motion of the teeth of the wheel 12.

Wheel 12 is then released, and spring 4 of wheel 7 urges wheel 12 clockwise until edge 8 of segment 6 stops at cam 9 of

bushing 2. Upon release of wheel 12, edge of slot 17 also removes from projection 15 of idler 13, which again is turned clockwise by the tensioning helical spring 4 in wheel 10 and follows edge 19 in wheel 12.

During the movement of wheels 12 and 13, and consequently, of type roller 23, the selection of additional information may have been already initiated by engaging shaft 1 for the next revolution by 180°. Selection of this second or additional information is carried out with locking wheel 14 having followed with constant speed the revolution of drive shaft 1 due to helical spring 4 provided in wheel 11.

When selecting the second piece of information, the magnetic system 28 receives a current impulse when the position of the locking wheel 14 coincides with the information intended for printing and stored in the register. The current impulse causes the armature 29 to be attracted, while pawl 30 is pushed into the gap between spaced teeth of wheel 14 coinciding with the read-out information.

It is possible that type roller 23 is still in a position which does not correspond to the information to be printed out. Roller 23 and idler 13 are still capable of achieving the catch-up operation, while the position to be resumed is already determined at locking wheel 14. If idler 13 still accomplishes

the catch-up movement by virtue of the tensioned helical spring 4 in wheel 10, such movement may be limited by pin 16 moving into engagement with the edge 20 of slot 18.

When the second revolution by 180° of drive shaft 1 is terminated, information determined by the locked position of wheel 14 and prepared in type roller 23 is printed. At that time, helical spring 4 in wheel 7 has moved wheel 12 so that edge 8 of segment 6 moves into engagement with cam 9 of bushing 2, thus insuring that wheel 12 goes on turning with the speed predetermined by the revolution of drive shaft 1.

Selection of a third piece of information after the printing of the second piece of information again occurs by energizing of magnet system 24 in synchronization with locking wheel 12 rotating with steady speed.

Within the scope of the invention, a great number of modifications of the embodiments as disclosed is possible. Helical springs 4 may be allowed to act directly on locking wheels 12, 14 and on idler 13 respectively. Moreover, there may be used three or four locking wheels instead of the two locking wheels

12, 14 used in the instant case, said locking wheels becoming effective consecutively in a cycle. Circumference of locking wheels must be modified subject to the subdivision made accordingly.

Obviously many modifications and variations of the present invention are possible in light of the above teachings. It is, therefore, to be understood that within the scope of the appended claims the invention may be practiced otherwise than as specifically described.

What is claimed is:

1. Apparatus for printing available coded data having type wheels individually arrestable in a printing position, comprising, idler means provided for each type wheel and firmly coupled to its respective type wheel, at least two locking wheels positioned independently of said idler means and of each other, a drive shaft, said locking wheels and said idler means being driven independently by said drive shaft, means for arresting each of said locking wheels from movement, each of said locking wheels being provided with stop means for engaging and preventing advancement of said idler means as compared to each of said locking wheels, and said arresting means being controlled in accordance with the data to be printed consecutively and being urging alternately into engagement with the locking wheels, one each for each printing operation.

2. Apparatus as recited in claim 1, wherein said idler means and said locking wheels are coaxially arranged and pivotally mounted independently of each other, and an appertaining wheel means mounted resiliently on the drive shaft for driving each said locking wheel.

3. Apparatus recited in claim 2, and additionally, stop means mounted on said drive shaft, said appertaining wheel means having a segment formed in one surface thereof with an edge thereof being movable with said drive shaft in a path in which said stop means is positioned, said edge engaging said stop means when said appertaining wheel means is returned to a normal position subsequent to a printing operation.

4. Apparatus recited in claim 2, and additionally, means for resiliently driving said appertaining wheel means including a helical spring having its inner end fixed at the drive shaft and the outer end of which attach at said wheel means.

5. Apparatus as recited in claim 1, wherein said locking wheels are arranged on opposite sides of said idler means, each of said locking wheels being formed with a semi-circular

slot formed therein, said slots in said locking wheels being displaced relatively to each other by 180° in an idle position, said idler means being formed with two projections displaced relatively from each other by 180° and on opposite sides of each of the locking wheels, each projection being located in the semi-circular slot of the locking wheel adjacent to the side of the idler means from which the particular projection extends to limit movement of the idler means when the locking wheel is prevented from moving.

6. Apparatus as recited in claim 2, wherein said appertaining wheel means is fitted with a toothing for the drive, and the arresting means engage the toothing on said locking wheels.
